UNITED STATES PATENT OFFICE.

BESSIE M. CHESTER, OF LONGBEACH, CALIFORNIA.

DESIGN FOR A WOVEN PALM-LEAF BASKET.

44,747.

Specification for Design.

Patented Oct. 21, 1913.

Application filed July 7, 1913. Serial No. 777,743. Term of patent 7 years.

To all whom it may concern:

Be it known that I, BESSIE M. CHESTER, a citizen of the United States, residing at Longbeach, in the county of Los Angeles and State of California, have invented a new, original, and ornamental Design for Woven Palm-Leaf Baskets, of which the following is a specification, reference being had to the accompanying drawing, forming a part thereof.

Figure 1 is an elevation and Fig. 2 a plan view of a basket showing my new design.

I claim:—

The ornamental design for a woven palm leaf basket as shown.

BESSIE M. CHESTER.

Witnesses:

C. W. CHESTER,
J. D. HASKIN.
